HARRIS C. ROTH, OF CHICAGO, ILLINOIS.

CARBURETER.

1,045,613.

Specification of Letters Patent. Patented Nov. 26, 1912.

Application filed July 29, 1911. Serial No. 641,310.

To all whom it may concern:

Be it known that I, HARRIS C. ROTH, a citizen of the United States, residing at Chicago, in the county of Cook and State 5 of Illinois, have invented a new and useful Improvement in Carbureters for Explosive-Engines, of which the following is a complete specification.

The present invention relates to carbureters for explosive engines, and includes an improved construction and arrangement whereby the quantity and quality of the mixture are automatically and positively controlled. A single actuated mechanism is 15 provided which will control the degree of opening of the port through which the mixture escapes to the engine, the degree of opening of the air inlet and the air passageway in which the oil inlet is located, and will 20 maintain a definite opening ratio between the several openings.

The preferred construction of the improvement is illustrated in the accompanying drawings, in which—

25 Figure 1 is a vertical section of a carbureter embodying my improvement; Fig. 2 is a plan view of same; Fig. 3 represents a side elevation of the carbureter, showing more clearly the operating levers for same; Fig. 30 4 is a transverse section of the carbureter taken on the line 4—4 of Fig. 3; Fig. 5 is a detail perspective of the parts constituting the chief novel features of the improvement; and Figs. 6 and 7 are views illustrating cer- 35 tain details of construction of same.

The carbureter body is comprised of the two parallel side plates 1, 1, which are secured at their upper ends to head 3, preferably by means of the screws 4, as shown 40 in Fig. 3. The carbureter head 3 is designed to be secured to the engine cylinder (not shown) by means of suitable bolts (not shown) engaging the holes 5. The said head 3 is provided with an opening or port 6, 45 through which the mixture is drawn into the engine. This port, as shown in Fig. 2, is rectangular on the lower side of the head, but merges into a circular opening above.

Between the plates 1, 1 are hinged on the 50 pins 7, 7 the oppositely disposed coacting plates 8, 8, which terminate at their upper ends adjacent the mixture port 6, forming an adjustable closure for same. The ends of the plates 8 are preferably made with the 55 outwardly curved portions 9. As the plates swing to or from each other they will close

or open the port 6. The under side of the head 3, where the curved portions 9 of the plates contact, is provided with a corresponding curve 3', so that practically an air 60 tight fit is obtained here as well as between the said plates and side walls 1, 1. The plates 8 are formed with the corresponding opposite outwardly curved portions 10, 10, the corresponding opposite inwardly curved 65 portions 11, 11, and near the upper ends the corresponding opposite outwardly curved portions 12, 12. That portion of the carbureter which lies within the walls 1 and between the portions 10, 10 of the plates 8 70 may be regarded as the air chamber 10'; the corresponding space between the inwardly curved portions 11, 11 may be regarded as the contracted air passageway 11', in which the oil inlet is placed, and the correspond- 75 ing space between the outwardly curved portions 12, 12 of the plate constitutes the carbureting chamber 12'. The air inlet 13 lies between the hinge pins 7 of the plates 8 and is controlled by means of the hinged plates 80 14, 14, which constitute the air valve. These hinged plates are oppositely arranged; their hinge centers are coincident with that of the plates 8, 8 on the pins 7, 7, and the said plates are connected with each other through 85 the toggle joint formed of the links 15. Se- cured to the joint pin 16 of the links 15 is the guide plate 17, slotted at 18 to engage the partition wall 19. The function of the said 90 toggle joint and the slotted guide plate 17 95 is to connect the air valve plates 14 in such a manner that when closing or opening movement is imparted to one a correspond- ing movement will be imparted to the other. The air valve plates 14, as well as the mix- 100 ture port closing plates 9, are actuated by a system of levers to be hereinafter described. Corresponding inward and outward move- 105 ment of the plates 8, 8 is effected as follows: A shaft 20, parallel with the pins 7, has bearings in the walls 1 of the body and ex- tends through the mixing chamber 12' be- 110 tween the plates 8. A lever 21, extending equal distances on each side of said shaft 20, is secured thereto, and the links 22 connect the ends of said lever to the plates 8, the ar- 115 rangement being such that rotation of the shaft will cause the free ends of the plate to approach or recede from each other to effect the opening or closing of the mixture port 6.

In the contracted air passageway 11', be-

tween the inwardly curved portions 11 of the plates 8, is the oil inlet 23, which extends in a direction parallel to the said plates. The oil inlet comprises a tubular conduit or 5 pipe 24, shouldered at 25 to engage the side walls 1, 1 and thus form a distance piece between said walls. The conduit 24 connects with the constant level cup 26 through the pipe 27. The constant level cup is provided with the float 28 which operates the oil admission valve 29, through the levers 30. The height of oil level is regulated by adjusting the fulcrums of the levers 30, which fulcrums are carried on the lower end of 10 the adjusting rod 31. The constant level cup 26 is fed through the pipe 32 from a constant source of supply, not shown. The tubular conduit 24 of the oil inlet is surrounded by a shell 33, the bore of the shell 20 being slightly larger than the diameter of the conduit, so that a comparatively thin annular space or reservoir 34 is made to surround the said conduit and extend throughout the length thereof within the body of 25 the carbureter. The conduit 24 is provided with the valve opening 35, controlled by the needle valve 36, said valve opening leading into the annular reservoir 34. The oil level in the constant level cup 26 is maintained at 30 such a height that when the needle valve 36 is opened the oil will flow into the reservoir, but will not overflow through the longitudinally extending slots 37 which are formed in the upper side of said shell 33. The slots 35 37 are so situated that the air in passing at high velocity through the contracted passageway 11 will entrain a fine spray of oil drawn out of the oil inlet by the partial vacuum in the mixing chamber and thus 40 effect a thorough mixture of same. The small quantity of oil which collects in the reservoir 34 when the needle valve is first opened will insure the initial charge being sufficiently rich to effect an easy starting of 45 the engine. After the engine is started the reservoir will be empty, the oil passing directly from the oil outlet 35 through the slots 37 into the mixing chamber.

The partition wall 19 extends from a position near the hinge pins 7 of the plates 8, 8 upwardly and midway between said plates, terminating at and being secured to the shell 33, thus dividing the air chamber 10' into two lateral compartments. The function 55 of the partition 19 is to furnish a support for the guide plate 17 and to deflect equal quantities of air on either side of the oil inlet 23.

From the foregoing it will be seen that 60 inward movement of the plates 8, 8 will operate to close the mixture discharge port and also diminish the size of the air passageway 11', while corresponding movement of the plates 14 will operate to close the air 65 inlet 13. The construction and arrangement

of the two pairs of plates are such that the opening of the mixture port is always equal to or slightly greater than the opening of the air inlet; while the extent of opening of the contracted air passageway is always less than that of the mixture port, thus resulting in the proper vacuum being maintained in the mixing chamber. A single system of levers is made to control the movements of the parts, so the results obtained are the control 70 by single means of the mixture port, the air passageway and the air inlet and the maintaining of a definite opening ratio between these several parts. 75

The limiting positions of the two pairs of plates are made adjustable, and the plates or valves are operated by the following means: To the shaft 20 is secured the bell crank lever 38, having the horizontally extending arm 39 and the upwardly extending arm 40, which connects with suitable means (not shown) to the lever controlled by the operator. Movement of the arm 39 will rock the shaft 20, effecting movement of the plates 8, 8, the extent of movement of this arm being 80 determined by means of the adjustable stops 41 and 42 (see Fig. 7). In the body of the carbureter, near the lower end thereof, is journaled the rock shaft 43, which is provided with the arm 44 on its end, as shown 85 in dotted lines in Fig. 1, and the arm 45 intermediate of the length of said shaft. The arm 45 is provided with an arcuate slot 46 whose center of curvature is coincident with the pivotal center 47 of the link 48 with the hinged valve plates 14 when said plates are 90 in their closed position. The link 48 affords, through the slot 46, an adjustable connection between the valve plates and arm 45. The adjustable end of the link 48 connects with 95 said arm by means of the sliding block 49, which moves in said slot and engages the end of the link. The sliding block 49 is engaged by the threaded rod 50, the said rod being rotatable in but held against longitudinal movement by the swivel standard 100 105 51. By rotating the rod 50 the effective length of the arm 45 is controlled, and hence the extent of opening of the air valve plates 14 is regulated. Since the center of curvature of the slot 46 is coincident with the pivotal center of the link 48 with the plate 14 when in closed position of plate, adjustment of said block in the slot will affect the extent of movement of the plates but will not 110 115 affect their closed position. The lever 39 on the rock shaft 20 connects with the arm 44 on the rock shaft 43, so that movement of the arm 40 will effect movement of both pairs of valve plates 8, 8 and 14, 14, thereby simultaneously controlling the mixture port 6, the air passage 11 and the air inlet 13 by means of a single acting device.

In starting the engine the carbureter is adjusted by means of the threaded rod 50 to 120 125 130

give the correct proportion of mixture for low speed, after which these proportions will be maintained, the ratio of valve openings and air passageway kept constant and the 5 quality of the mixture held uniform for any degree of opening or engine speed.

What I claim as my invention, and desire to secure by Letters Patent, is:

1. In a carbureter for explosive engines, in 10 combination, a body formed with parallel sides and provided at its upper end with a mixture discharge port and at its lower end with an air inlet, two oppositely disposed coating plates within said body, said plates 15 being hinged at their lower ends, curved inwardly intermediate of their length to form a contracted air passageway and terminating at their upper ends adjacent the mixture discharge port thereby forming an adjustable closure for same, an oil inlet located in the air passageway between the inwardly curved portions of said plates which thus 20 regulate the air velocity around the inlet, a valve for regulating the air inlet, and suitable mechanism arranged to simultaneously 25 actuate the said hinged plates and air valve, substantially as described.

2. In a carbureter for explosive engines, in combination, a body formed with parallel 30 sides and provided at its upper end with a mixture discharge port, a pair of opposed plates closely fitting within said body, said plates being curved inwardly intermediate of their length, hinged at their lower ends 35 and terminating at their upper ends adjacent said port, an oil inlet in said body located between the inwardly curved portions of said plates, the plates thus forming

adjustable walls of a mixing chamber above the oil inlet and adjustable walls of an air 40 chamber below said inlet, a pair of adjustable downwardly projecting plates forming an air valve, said plates being hinged on centers coincident with the hinge centers of the upwardly projecting plates, and single 45 acting adjustable mechanism arranged to simultaneously actuate both pairs of hinged plates thereby regulating the degree of opening of the air inlet, the mixture port and the air passageway around the oil inlet and 50 maintaining a definite opening ratio between the several openings, substantially as described.

3. In a carbureter for explosive engines, in 55 combination, a body provided with a mixture discharge opening and an air inlet, a pair of upwardly extending coating plates curved inwardly intermediate of their length and arranged to form with their free ends an adjustable closure for said mixture 60 port, an oil inlet located in the passageway formed by the inwardly projecting portions of said plates, an air valve comprised of a pair of downwardly extending hinged plates, the hinge point being coincident with 65 said first mentioned plates, a partition extending midway between the plates from their hinge centers upwardly to the said oil inlet, an adjustable system of levers for positively operating the two pairs of hinge 70 plates, and single means for actuating said system of levers, substantially as described.
